UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR CONSTRUCTION.

Application filed December 10, 1921. Serial No. 521,292.

To all whom it may concern:

Be it known that I, ARGYLE CAMPBELL, a citizen of the United States, residing at Chicago, in the county of Cook and State of Illinois, have invented a certain new and useful Improvement in Car Constructions, of which the following is a full, clear, concise, and exact description, reference being had to the accompanying drawings, forming a part of this specification.

This invention relates to improvements in car construction.

In dump cars, considerable difficulty has heretofore been experienced in preventing tearing out and corroding at certain points in sheets due to inherent weaknesses developed in the bending and forming of the sheets. These difficulties are especially frequent at the juncture of the bottom and side sheets of a hopper car adjacent the hinge points of the doors where the metal is generally bent from one plane to another. Due to the failure of such points in the car construction, much expense is incurred in repairing pairs and loss of earning power.

One object of my invention is to provide a simple and relatively inexpensive reinforcing brace for certain portions of the sheet metal parts of the car construction to thereby prevent the same from tearing out.

Another and more specific object of the invention is to provide a combined floor stiffener hinge butt and corner brace for dump cars.

In the drawings forming a part of this specification, Figure 1 is a side elevational view of a portion of a drop bottom dump car, showing my improvements in connection therewith. Figure 22 is a vertical, sectional view, taken transversely of the car, from the side to the center sill thereof and corresponding substantially to the section line 2—2 of Figure 1. Figure 3 is a top plan view of the improved combined floor stiffener hinge butt and corner brace, detached, such as shown in Figures 1 and 2. Figures 4 and 5 are detail, transverse sections of the combined stiffener and brace and corresponding to the section lines 4—4 and 5—5 respectively of Figure 3. And Figure 6 is a view similar to Figure 2 illustrating my improvements applied to a slightly different type of car.

Referring to the construction illustrated in Figures 1 to 5 inclusive, 10 denotes one

of the floor sheets of the car, 11 the outer side hopper sheet, 12 the inner side hopper sheet and 13 one of the channels of the center sill girder.

In the particular type of car shown, two 60 hinged bottom doors 14—14 are employed, the same having their free edges meeting when the doors are in closed position. Each of said doors is adapted to be hinged about an axis extending transversely of the car at 65 the free edge of the corresponding bottom sheet, by means hereinafter described.

As shown the outer side hopper sheet 11 is secured along its upper edge to the side wall 15 of the car, is then extended downwardly and inwardly as indicated at 16, and thence downwardly vertically as indicated at 17, the bottom edge of said sheet 11 where engaged by the doors, being formed with an outwardly extending flange 18 which is then 75 bent vertically downward as indicated at 19 in a plane outwardly offset from the plane of the section 17, to thereby provide a better seal for the door when the latter is in closed position. The inner side hopper sheet 12, at 80 the lower portions defining the hopper discharge opening, extends vertically as shown in Figure 2 and along its lower edge is flared outwardly as indicated at 20 and thence downwardly in a vertical plane as indicated at 21, similar to the other outer side hopper sheet 11. As clearly indicated in Figure 1, the lower edge portions of the side hopper sheets, between the hinge joints, converge downwardly to conform to the inclined positions of the doors when the latter are in closed position.

To stiffen and reinforce the lower transversely extending edge 22 of the floor sheet 10 along the line of the hinge connection 95 of the door, I employ a combined floor stiffener and hinge butt designated generally by the reference character A. As best shown in Figures 3, 4 and 5, said combined stiffener and hinge butt is provided with a main 100 web 23 extending under and for the full width of the bottom sheet 10 and rigidly secured thereto as by the series of rivets 24—24. Along the lower edge, that is, the edge substantially flush with the edge 22 of the 105 floor sheet 10, said stiffener and hinge butt A is formed with a relatively narrow depending flange 25 extending the full length of the stiffener as best shown in Figure 3. Along the opposite edge of the main web 23, 110

the member A is provided with another downwardly extending flange 26, said flange 26 extending the full length of the member A. The two flanges 25 and 26 are extended 5 at right angles to the main web 23, that is perpendicular to the inclined floor sheet 10. The wider flange 26 may be additionally strengthened by a narrow lip 27 extending at right angles to the flange 26 and away there- 10 from, parallel to the main web 23.

Intermediate its ends and at suitable points corresponding to the hinge butts secured to the door, the member A is provided with pairs of depending, relatively heavy, 15 spaced ears 28-28 perpendicular to the main web 23 and also perpendicular to the main flanges 25 and 26. The ears are provided with alined openings 29 adapted to accommodate heavy headed hinge pins 30- 20 30 which also extend through suitable eyes 31 formed on the double-cover hinge straps 32 secured to the under side of the door.

Opposite each pair of ears 28, the casting A is additionally reinforced by web sections 25 23^a continued in the plane of the web 23, said web sections 23^a being in turn braced by triangular shaped flanges 33-33 extending in vertical planes and depending from the web sections 23^a.

30 With the construction of combined floor stiffener and hinge butt above described, it is evident that the same thoroughly braces and reinforces the lower or free edge of the floor sheet and serves to prevent the latter 35 from bending under the loads imposed thereon at the two points of support for the door. The member A serves the double function of the usual angle iron reinforcement and independent hinge lugs, thus minimizing the cost of application, and furthermore a very efficient seal is obtained between the flange 25 of the member A and the edge flange 14^a of the door.

Due to the outward flanging of the side 45 hopper sheets 11 and 12 at points opposite the ends of the line of the free edge 22 of the bottom sheet 10, it will be noted that corners of peculiar form are produced in the bending and forming of the sheet which, 50 if not properly taken care of, will easily tear under the loads imposed thereon and are also particularly subject to corrosion due to the inherent weaknesses set up in the metal at these points because of the stretching and deformation thereof.

To compensate for the necessarily weak structure developed at the points mentioned in the side hopper sheets, I form the member A with additional end flanges to 60 form to and fit over the different portions of the side hopper sheet. At each end, the member A is provided with a vertically extending flange 34 which fits against and is riveted to the vertical section 17 or 12 of 65 the corresponding side hopper sheet. The

end portion of the member A is additionally provided with an outwardly extended flange section 35 fitting over the top of the flange section 18 or 20 of the corresponding side hopper sheet 11 or 12. At each end the 70 member A is additionally provided with a downwardly extending flange section 36 fitting over and against the corresponding vertically extending flange section 19 or 21 of the respective side hopper sheet 11 or 12. 75 As best shown in Figure 1, the flange sections 36 of the member A are sufficiently extended to cover the ends of the joint formed between the hinge edge of the door and the free edge of the bottom sheet 10, thus providing an additional seal to prevent escape of any of the load as well as strengthening the sheet metal at these points. As will be understood, the outwardly extended flange sections 35 of the member A conform in 80 slope to the slope of the corresponding flange sections 18 or 20 of the side hopper sheets, as clearly shown in Figures 1 and 2. The flange sections 34, 35 and 36 at each 85 end of the member A are braced by means of ribs 37 extending in planes at right angles to the flanges 34 and 36.

The construction illustrated in Figure 6, so far as concerns the combined floor stiffener, hinge butt and corner brace A', is the 95 same as that shown in the other figures except that the corner brace feature is employed at one end only, viz: the outer end, inasmuch as the inner side hopper sheet 112 has no offset flange sections and is otherwise braced where it joins with the floor sheet by means of an angle iron 38 riveted to the side sheet 112 and the lower flange 100 of the center sill channel 113.

I have herein shown my improvements as 105 the same would be applied to two different types of dump cars, but it is obvious that the invention may be employed with many different other types of dump cars with suitable modifications of the various flange sections of the brace to conform to the particular formations of the floor and side hopper sheets of the car, without departing from the spirit of the invention. It will also be observed that my invention may be embodied in corner braces made separate from the floor stiffeners and hinge butts. All changes and modifications are contemplated that come within the scope of the claims appended hereto.

120 I claim:

1. In a load discharging car having an opening in the bottom thereof, car floor and car wall members defining said opening, a door for closing said opening, a member for uniting said car floor and car wall members, said uniting member having flanges in angular position to each other, one flange extending under the car floor and the other outward of the car wall.

2. As an article of manufacture, a corner brace for a car floor and a side sheet, said corner brace having integral flange portions adapted to extend under the floor sheet and over an adjacent portion of the side sheet and to be secured to both sheets. 5
3. In car construction having a floor sheet, side sheet, and door pivotally attached at the edge of the floor sheet, a brace 10 having a flange portion underlying and secured to the floor sheet, and flange portions extending over the side sheet and secured thereto, one of said flange portions of the brace also extending over the end of the line of meeting of the hinge edge of the door and the adjacent edge of the floor sheet. 15
4. In car construction, the combination with a floor sheet, side sheets, and door; of a combined floor reinforcement and hinge 20 butt extending lengthwise of and secured to the edge of the floor sheet, said combined reinforcement and hinge butt having a flange at one end thereof overlying the side sheet opposite the end of the line of meeting between the door and bottom sheet; and means for pivotally attaching the door to said hinge butt. 25
5. In car construction having a floor sheet and a side sheet, the latter having laterally 30 offset flanged edges, a brace having flange portions extending beneath the floor sheet, over the side sheets and secured thereto, said brace having also laterally offset flange portions conforming to and fitting against the laterally offset flanged edges of the side sheet. 35
6. In a car having a floor sheet extending in one plane, a side sheet extending in a different plane, said side sheet having laterally offset portions adjacent the junction 40 with the floor sheet, the combination with a combined floor sheet stiffener and hinge butt member extending lengthwise of and secured to the under side of the free 45 edge of the floor sheet, said member at one end thereof having flange sections fitting over the outer sides of the side sheet and the laterally offset flanged edges thereof; and a door pivotally attached to said member. 50
7. The combination with a floor sheet of a car, of a reinforcing hinge plate secured near the edge thereof, said plate being provided with a flat portion contiguous to said 55 floor sheet, the front edge thereof substantially paralleling the rear edge of the door, transversely extending ribs provided with openings therein adapted to receive the hinge pins, and an extension at an end of 60 said member projecting at approximately right angles thereto and lapping around the adjacent member of the car. 65
8. The combination with a floor sheet of a car, of a reinforcing hinge plate secured near the edge thereof and adjacent the car 65
- door, said plate being provided with a flat portion contiguous to said floor sheet, also an angular reinforcement at the under side thereof, transversely extending ribs between the flat portion and the angular reinforcement and provided with pin holes suitable for cooperation with the car door hinges, and an extension on said plate at an end thereof for maintaining the adjacent hopper sheet in close relation to the floor sheet. 70
9. As an article of manufacture, a combined floor brace, multiple hinge butt and corner brace for holding in fixed relation a floor sheet, side hopper sheet and car door and having portions arranged to overlie 80 and be united with the floor sheet and side sheet. 75
10. The combination in a hopper car having doors for the discharge of the load, side hopper sheets, floor sheet and door, of a one-piece member arranged to be united with and brace the side hopper sheets to hold same in their original position and to be united with and brace the floor sheet from depression, said member having hinge 90 butts for the car door for use in position adjacent the rear edge of the car door. 95
11. As an article of manufacture a one-piece member suitable for application to a car body, comprising a side sheet brace, floor sheet stiffener, hinge butt, and car door seal, said member having portions arranged to overlie and be united with the side sheet and floor sheet. 100
12. As an article of manufacture, a corner brace for two car sheets intersecting each other at an angle and one of which terminates with a free edge at the point of intersection, said corner brace having integral portions extending in planes corresponding 105 to the intersecting planes of the car sheets and adapted to be secured to the respective car sheets, one portion of said brace extending parallel to and adjacent said free edge of one of the sheets. 110
13. In a dump car having a discharge opening defined by a sloping bottom sheet terminating with a horizontally extending free edge and side hopper sheets, the planes of the bottom sheet and the side sheets intersecting at an angle, the car having a door pivotally supported from said bottom sheet to swing about an axis parallel to the free edge of said bottom sheet, and a corner brace having integral portions overlapping 120 the under side of said bottom sheet and one of the side sheets, said portions being adapted to be rigidly united with the adjacent corresponding portions of the bottom and side sheets. 115
14. In a load discharging car having an opening in the bottom thereof formed of longitudinal members and inclined transverse member, a door hinged adjacent said transverse inclined member for closure of 130

said opening, a supplemental member for uniting the said longitudinal and transverse members and resisting the pressure against said members and for strengthening the 5 same at their junction adjacent the rear edge of the car door.

15. In a car body having side walls, inclined floor members, a discharge opening in the bottom thereof and door for closing 10 said opening, a stiffener member disposed adjacent the rear edge of the door and presenting angularly disposed flanges for tying the car floor member to the side walls, one of such flanges extending beneath the 15 inclined floor and the other of such flanges extending outside of the car wall.

16. In a car body having side walls, inclined floor members, a discharge opening in the body thereof and a door for closing 20 said opening, a connecting member disposed adjacent the rear edge of the door and presenting angularly disposed flanges, one of such flanges overlying the car side wall and secured thereto and the other of such flanges 25 being of angular section and extended beneath the inclined floor and secured thereto.

17. In a hopper car having an inclined floor sheet, side wall and door pivotally attached near the edge of the floor sheet; 30 means for securing the said inclined floor and side wall together, said means comprising a brace having a flange portion underlying and secured to the floor sheet and having a flange portion extending over the side 35 wall and secured thereto.

18. In a hopper car having an inclined floor sheet, side wall and door pivotally attached near the edge of the floor sheet; a

member adapted to support the door and secure the said inclined floor and side wall together, said member comprising a brace having a flange portion underlying and secured to the floor sheet and having a flange portion extending over the side wall and secured thereto. 40

19. In a hopper car having an inclined floor sheet, side walls to each side thereof and a door pivotally attached near the edge of the floor sheet; a member adapted to support the door and secure the said inclined floor sheet and side walls together, said member comprising a brace having a flange portion underlying and secured to the floor sheet and having flange portions extending to the side walls of the hopper and secured 55 thereto.

20. As an article of manufacture, a brace for two car sheets intersecting each other at an angle, one of which is arranged to sustain a load on its upper side, said brace having integral portions extending in planes corresponding to said intersecting planes of the car sheets, one portion of said brace extending beneath and secured to the underside of said load-sustaining sheet and another portion of said brace extending along and secured to the outer side of the other of the car sheets. 60

In witness that I claim the foregoing I have hereunto subscribed my name this 28th 65 day of November, 1921.

ARGYLE CAMPBELL.
